UNITED STATES PATENT OFFICE.

EDWIN L. ELWELL, OF BALTIMORE, MARYLAND.

MACHINE FOR MANUFACTURING CRIMPED PAPER CUPS.

Application filed April 16, 1921. Serial No. 461,855.

To all whom it may concern:

Be it known that I, EDWIN L. ELWELL, a citizen of the United States of America, residing in the city of Baltimore, State of Maryland, have invented certain new and useful Improvements in Machines for Manufacturing Crimped Paper Cups, of which the following is a specification.

This invention relates to a machine for producing paper wrappers or cups used in packing or wrapping or as a receptacle for individual candies or pieces of candy, as chocolates, bon-bons and the like; the wrappers or receptacles being usually and preferably in the form of paper discs having a flat circular central portion constituting the bottom of the cup and having a wide margin or edge portion which is crimped or pleated to form the walls or sides of the cup. Several machines for this purpose are known to the patented art, the present invention being understood to relate to certain improvements or to an improved type of machine.

The machine as shown which is an embodiment of the preferred form of the invention consists of a dial or carrier plate having a step by step rotation and a plurality of dies with which openings or pockets in the dial register at each dwell in combination with two separate reciprocating heads carrying a cutter and a bumper and punch respectively and timed and placed as hereinafter described, to cooperate with the dial and dies together with means for feeding a web of material as paper, whereby blanks are cut from the web of paper by means of the reciprocating cutter acting in cooperation with one of said dies known as the cutting die and carried by the dial to the other reciprocating head, which crimps the blanks thus cut acting in connection and in combination with the other die, the parts being so arranged and placed that the dial in its step by step rotation brings each set of blanks cut by the cutter, into cooperative relation with the crimping die to be acted upon as aforesaid.

An important feature of the machine resides in the crimping means which includes a bumper which strikes the blanks forcing them into the serrations of the crimping die where they are held not by positive but by a spring tension provided by means of springs which take up an excessive backlash or play in the bumper mechanism provided for that purpose, the opera-

tion being completed by the action of a punch which is timed a little later than the bumper and which serves to draw the crimped portion of the blanks thru the die between the bumper and the die, overcom-
ing the spring tension which tends to hold the bumper against the die and perfecting and completing the crimping action as more fully hereinafter explained.

Other features of the machine relate to the step by step motion of the dial which is preferably driven in connection with the bumper and punch and may be positioned by the bumper and punch mechanism or means carried thereby or causing the dial to stop with a pocket or opening carrying the paper blanks in registration with the die and in the path of the punch and bumper.

In order to provide for the cooperation of the cutter with the dial, means are provided for stopping the cutter or the reciprocating head by which it is carried whenever the dial with its carrier openings or pockets move out of registration or out of alignment with the cutter. This in the present instance is accomplished by withdrawing a key which connects the reciprocating mechanism carrying the cutter to its drive shaft.

In the form of the machine shown, the cutter and die are driven by separate belts, the dial as aforesaid being timed to cooperate with both said mechanisms.

In the accompanying drawing I have illustrated a cutting and punching machine for producing paper cups or wrappers embodying the various features of my invention in the preferred form.

In the drawings:—

Fig. 1 is a front elevation of the machine.

Fig. 2 is a view looking to the right in Figure 1 from the plane indicated by line 2—2 in Figure 1, same being partly in section.

Fig. 3 is a view looking toward the left in Figure 1, taken on and from a plan indicated by the line 3—3 in Figure 1.

Fig. 4 is a detail view of the timing mechanism operating in connection with the reciprocating head which carries the cutter, the dial serving to maintain the proper timing relation between the cutter and dial.

Fig. 5 is a detail of the clutch mechanism embodied in the timing apparatus.

Fig. 6 is a section on the line 6—6 of Figure 5.

Fig. 7 is a vertical central section through

the bumper and punch mechanism, i. e., the reciprocating head carrying the bumper and punch taken on the longitudinal plan of the axis of the machine.

5 Fig. 8 is a plan of the turn table and driving gear for the same, the gear casing being shown in section.

Fig. 9 is a horizontal section on the line 9—9 of Fig. 2.

10 Figs. 10 and 11 are views of the cup or wrapper made by the machine.

Referring to the drawings by numerals, each of which is used to indicate the same or similar parts in the different figures, the machine as shown comprises two reciprocating heads indicated in a general way by reference characters 1 and 2 respectively, an intermittently rotating dial 3 and suitable cutting and forming dies.

20 The reciprocating head 1 being the cutting head and the reciprocating head 2, the die pressing or bumping and punching head. In the form of the invention shown, the cutting and die pressing heads are separately driven. The reciprocating head 1 being driven by means of a suitable belt 5, which engages a pulley 6 on a shaft 7, which shaft at the end 8 is provided with an offset or crank 9 carrying a crank pin 10 which actuates a connecting rod 11, connected at its lower end by a suitable wrist pin and bearing 12, to a sliding cross head 13 which reciprocates in suitable stationary upright guides 14. It will be noted that as shown 30 the throw of the crank 9 is adjustable by means of an eccentric 15 enclosing and surrounding the crank pin 10 within the connecting rod bearing 16 at the upper end of the connecting rod. The manner of adjustment is by loosening the bearing 16 and rotating the eccentric.

40 The cross head 13 carries a cutter 17 which cooperates with a circular die 18, cutting circular blanks, or blanks of the desired shape according to the form of the cutting die from a web or webs 19, fed over the die and beneath the cover plate 20 as hereinafter described. The webs are ordinarily fed in multiple.

45 Referring now to the opposite end of the machine, particularly to the die pressing and punching head 2, the die pressing and punching mechanism is driven by means of an ordinary belt and pulley 220 and 21, the belt being in the illustration Fig. 1, shown as in engagement with the loose pulley 22 to which the belt may be shifted when the machine is idle. The pulley 21 is secured to drive shaft 23 which has a suitable bearing 50 in the frame of the machine at 24, and carries a toothed gear 25 rigidly secured to the pulley and meshing with a toothed gear 26 on a shaft 27. The cutter has suitably spaced bearings 28, 29 in the frame of the machine. At the opposite end of the shaft

55 27 from the toothed gear 26 and mounted on and rigidly secured to said shaft 27, is an eccentric 31, see Fig. 7 encircled by an eccentric strap 32 carrying an eccentric rod 33 connected by means of a wrist pin 34 to a reciprocating cross head 35, which travels in a vertical path in suitable upright guides 36.

An important feature of the invention relates to the provision of a considerable clearance 37 between the strap 32 and the eccentric, the eccentric strap being given a downward tendency by means of spiral springs 38 attached at their upper ends 39 to the strap and at their lower ends to stationary points on the machine at 40, the springs being normally under tension. This permits the mechanism to strike or to bump it on the die imparting an initial crimp, the positive pressure being removed as the eccentric rotates past its lower dead point and a resilient spring pressure being maintained which permits the paper to be drawn through the die by the punch, overcoming the spring pressure and producing a most satisfactory final crimping action as herein-after described.

The bumping or upper bumping die carried by the reciprocating cross head 35 is illustrated in Figure 7 in section and in Figure 2 in elevation, and indicated by reference character 41; it has a central aperture 42 in the direction of the stroke to provide for the passage of the punching or drawing die 43, the lower or stationary 50 pressing die indicated by reference character 44 is also centrally apertured to provide for the passage of the punching or drawing die 43 and of the finished cups or wrappers. The cooperating die surfaces of the upper or bumping die 41 and the lower stationary forming die 44, said surfaces being indicated by reference character 45 are serrated in corresponding radial ridges and grooves to produce corresponding crimps or pleats in the paper. The position of the upper or bumping die 41 relatively to the eccentric rod 33 is adjustable by means of an eccentric 46 enclosing and encircling the wrist pin 34 within the eye 48 of the wrist pin bearings at the upper end of the cross head 35; the manner of adjustment by rotation of the eccentric will be understood.

To actuate the punch 43 the eccentric 31 is provided with a crank pin 47 projecting from its outer face. The crank pin operates a connecting rod 50, the wrist pin 51 and sliding cross head 52, which likewise travels in guides 36. The punch 43 before mentioned, is mounted at its upper end in the lower end of the cross head 52 having in fact a shank 53 seated in an aperture in the cross head and held by a set screw 55.

To provide for the successive operation of the bumping and punching members, the

crank pin 47 as shown is set from 45° to 60° back of the point of maximum throw or greatest radius of the eccentric as indicated by reference character 56 in Fig. 2; the angle being widely variable from these figures and the direction of rotation being clockwise or right handed as seen in Fig. 2.

This arrangement permits the bumper or pressing die to strike its blow at the bottom 10 dead point of the eccentric acting with a positive pressure when all the back lash or play is taken up and then, i. e., after the eccentric 31 passes the dead point, the bumper or upper bumping die 41, is held in contact with the paper by the action of the 15 springs. After the positive pressure of the bumper has been released by rotation of the eccentric and while the paper is held between the upper or bumping die 41 and the 20 lower or stationary pressing die 44 by the tension of springs 38, the punch 43 comes in contact with the center of the paper blanks tending to push them downward through the apertures in the lower stationary pressing die 44, the same being indicated by reference character 49. This causes the edge 25 portions of the blanks to be drawn with a considerable degree of tension through the cooperating serrated surfaces 45, completing and perfecting the pleats or crimps in the paper as aforesaid.

Having further reference to the die pressing and punching head 2, the shaft 27 carries a sprocket 60 (see Fig. 1) which drives a chain 62 which in turn meshes with a sprocket 63 secured to a shaft 64 mounted in suitably spaced bearings 66 and carrying a web feeding roller 67. Cooperating with the roller 67 is an upper feed roller 68 on a 40 shaft 69 mounted in bearings 70 suitably spaced as aforesaid, it being understood that the bearings 70 and 66 are mounted in vertical ways or slots 71 in suitable standards or uprights 72, the bearings being semi-circular, the lower bearings 66 being turned up and the upper bearings 70 turned downward, also set screws 73 are threaded into the ends of the uprights 72 bearing at their 45 lower ends against the semi-circular bearings 70 whereby suitable tension or pressure is applied to the rollers regulating the contact pressure and providing suitable adjustment to the thickness of web or multiple web passed through the rollers. The upper roller 68 is driven by means of meshing 50 tooth gears 74, 75 on the lower and upper roller shafts 64, 69 respectively.

The rollers 67, 68 as aforesaid are intended to feed the paper web or webs for the machine uses the paper in multiple thickness in its normal operation, the feed being continuous and sufficient to supply a length of paper equal to the diameter of the blanks plus a suitable margin preferably 55 from a sixteenth to an eighth of an inch

between the cuts for each quarter turn of the dial, i. e., for each step in the rotation of the dial as hereinafter described. The die pressing or bumping and punching head 2 also includes means for imparting to the 70 dial 3 which in this instance has four pockets or apertures 275 equally spaced by arcs of 90° the step by step rotation aforesaid which places these pockets in turn in exact registration with the cutting die 18 and the 75 crimping die or stationary pressing die 44 and in alignment with the cutter 17 and the bumping and punching members 41 and 43 which are as aforesaid in alignment with the cutting die 17 and stationary pressing 80 die 44 respectively. It should also be noted that for efficiency and facility of operation the respective elements described are so arranged that the two opposite holes or pockets 275 spaced by 180° are brought simultaneously in registration, one with the cutting die and cutter, the other with the pleating die and bumper and punch. To this end the shaft 27 of the reciprocating head 2 carries a bevel gear 80 which meshes with a bevel gear 81 on an upright shaft 82 mounted in suitable bearings 83 in the frame, which shaft 82 carries in its lower end an intermittent or mutilated gear 84 having a portion of the circumference 85 of a length corresponding to one quarter of the circumference of the dial 3 toothed as shown, the remainder of the circumference 86 being smooth. At the end of the toothed portion 85, a tooth 87 is provided of double width and the dial 3, which has its circumference toothed at 88 to cooperate with the intermittent gear, is provided at intervals amounting to one quarter of the circumference or 90% with similar teeth 89 of double width and corresponding space 90 adjacent the said teeth to receive the double width teeth on the intermittent gear.

The double teeth are provided for the purpose of taking up the initial stress incident to starting the dial after each dwell. The double tooth 87 is shown in contact with a double tooth 89 on the dial in Fig. 8. In this position the dial is about to start a quarter rotation, the rotation of the dial being counter clockwise as illustrated. The tooth of the dial immediately adjacent each space 90 in the form illustrated is cut away at 91 to provide for the meshing of the gears.

It will be apparent that when the dial comes to the end of each quarter rotation bringing the pockets or holes 75 into registration with the dies, that it has considerable moment of rotation. To arrest the rotation of the dial and position it with the pockets in registration with the dies and alignment with the bumper and punch and cutter, the cross head 35 which carries the bumper is provided with a stop pin 95 car-

ried in a suitable socket 96 in the cross head. The stop pin 95 is set in a projecting portion or lug 98 on the cross head beneath the guide extending below the bump-
 5 cr. As the cross head descends the stop pin 95 enters holes 97 in the dial 3 being guided by stop blocks or abutments 99 spaced at 90° intervals, the engagement of the pin with the blocks is preliminary to its entrance into the corresponding hole 97. Each block and hole 97 is adjacent to and corresponds to a pocket so that the pin 95 engages the blocks in turn stopping the dial in exactly the position to locate the pock-
 10 ets in turn in registration with the dies and in alignment with the bumper, the holes serve to lock the dial at each dwell preventing displacement. Further the pin 95 on account of its length continues in engage-
 15 ment with the dial some time after the bumper cross head starts to move upward when the punch has entered the die. The continued upward traverse of the bumper cross head releases the dial as the double tooth 87 completes the rotation and comes in contact with the next double tooth 89 on the dial. The meshing of the teeth on the dial with those of the intermittent gear accomplishes another quarter revolution
 20 moving the next pocket into registration with the dies, the parts being so timed that the punch is completely or substantially withdrawn prior to the meshing of the tooth 87 so that it is moved from the path of
 25 the dial before the latter can come in contact with it.

Figs. 4, 5 and 6 illustrate the cutter timing mechanism by means of which the cutter is timed in exact correspondence with the step by step rotation of the dial so that at each dwell of the dial the latter is positioned with one of its pockets beneath the cutting die and each cutting operation serves to deposit in a pocket of the dial, which pocket is held in registration with the cutting dial, a cut blank or a number of cut blanks equal to the number of sheets composing the web.

To this end the pulley 6 which drives the shaft 7 which actuates the reciprocating cutter is mounted on the shaft to rotate relatively thereto and means is provided whereby the pulley is keyed to the shaft at intervals and released providing for the actuation of the reciprocating cutter at intervals corresponding to each dwell of the dial, during which the holes or pockets in the dial are positioned in alignment with the cutter and the cutting die. The face 50 of the pulley adjacent the shaft as shown in Fig. 5 and in dotted lines in Fig. 6 is provided with four notches or indentations 100 adapted to be engaged by a key or bolt 101 carried by a collar 102 which is keyed to the shaft by means of a key 103 to ro-

tate therewith. The key 100 is mounted to slide in the collar in the direction of the axis of the shaft being to this end seated in a groove 104 in the collar and held by suitable cover plates 105 secured by any suit- 70 able means.

A spring 106 seated in an aperture 107 in the key and bearing against the end wall 108 of the groove 104 serves to impart to the key a tendency to slide to the left in 75 the groove causing it to protrude from the collar and enter one of the notches or depressions 100. The key is also slotted transversely as to its outer face at 208 and the collar has a peripheral groove 109 and the 80 key has a follower or dog surface 110 at one side of the groove in the key which projects into the groove 109 in the collar when the key is advanced, i. e., projecting from the collar into one of the apertures 85 or depressions in the pulley. Cooperating with the follower or dog 110 is a cam 111 having a cam surface 112, the cam being formed on the lever 113 which is immediately pivoted at 114 on a suitable stationary support and adapted to swing into and out of the groove and into and out of the path of the dog or follower 110. 90

The shaft 7 has a right handed rotation as seen from the left in Fig. 5 tending to bring the dog or follower 110 into contact with the cam surface 112 when the cam is in the groove. The action of the cam on the follower throws the key to the right in Fig. 5 withdrawing it from the notches or 100 depressions in the face of the pulley and releasing the shaft from the pulley so that the shaft tends to dwell with the follower in contact with the cam and with the cutter in withdrawn or upper position. When the 105 cam is removed from the groove the key 101 is released, being projected by the pressure of the spring 106 into a notch or depression 100 of the pulley 6 which is in continuous rotation locking the pulley to 110 the shaft, causing the shaft to rotate and actuate the cutter.

The cam lever 113 is in part controlled by a spiral spring 116 attached at one end to the lever at the end opposite the cam 112 and to a fixed point 118 on the frame. The end 117 of the lever is also pivotally connected to a rod 119 which is connected at its opposite end to the swinging end 120 of a bell crank lever 121 pivotally mounted at 122 on the frame and having a depending arm 123 engaged by a sliding rod 124 in suitable bearings 125, 126 in the frame, which rod is normally controlled by a spring 127 coiled about the rod and bearing 125 at one end against the bearing 126 and at the other end against the collar 128 pinned on or otherwise secured to the rod. This rod 124 normally projects over and along the surface of the dial 3 into the path of 130

lugs 130, four in number, that is, corresponding in number to the pockets 75 and so related to the pockets that each lug 130 in turn comes in contact with the rod 124 6 thrusting it to the right as seen in Fig. 4, swinging the cam 111 out of the path of the follower or dog 110, releasing the key 101 permitting it to engage the pulley 6, whereby a single rotation is imparted to the shaft 10. 7 resulting in a single reciprocation of the cutter, causing it to operate once and cut a single blank or set of blanks from the web, it being understood that the lugs 130 are so related to the pockets or holes 75 and the 15 cutter is so timed as to operate during the dwell of one of the pockets 75 in registration with the cutting die and in alignment with the cutter.

The rotation of the shaft 7 is arrested by 20 the release of the key and by a brake to be described. The release of the key is accomplished at the end of each rotation of the shaft 7 by the cam 111 which is returned immediately to the groove 109 by 25 the action of the spring 16 when the lug 130 passes out of contact with the end of the rod 124 which is at the end of the dwell of the dial. The cam thus engages the follower surfaces 110 on the bolt 101 with 30 drawing the bolt, releasing the pulley and holding the bolt in withdrawn position till the next lug 130 comes into operation.

The brake is illustrated in Figs. 1 and 3 being indicated by reference character 135. 35 It consists of a circular band which is split and drawn together by means of a screw 136 engaging the separate ends. The band is provided with suitable brake lining 137 which bears against a drum 138 on the shaft 40 and the band is further provided with a projecting arm 139 which engages a fixed portion of the frame at 140 providing the desired retardation which immediately stops the shaft when it is released from the 45 pulley by the withdrawal of the key.

A suitable take-off is provided which serves to remove the cut web from the machine and to prevent its accumulation in the vicinity of the cutter. This take-off 50 may consist of a roller 141 driven by a belt 142 from a pulley 143 on the cutter shaft 7.

In operation the paper is fed by means of the rollers 67, 68, the feed preferably being continuous and at a rate which provides in excess of the dimensions of the 55 blanks a sufficient margin, something less than a quarter of an inch to hold the waste together and in line so that it may be conveniently drawn from the machine, the web 60 being also for this purpose slightly wider than the cut. It is easily understood that the flexibility of the paper web will permit it to buckle and take up the portion fed when the cutter is down, the web being in 65 turn released and caused to flatten and

thrust its front edge forward when the cutter is withdrawn.

The operation of the cutter 17 in connection with the cutting die 18 and the timing of the cutter in its relation to the dial have 70 been fully described, the entire stroke of the cutter is accomplished within or practically within the dwell of the dial, the dial being beneath the cutting die and having one of its pockets 75 in registration with the die at the 75 time of the cutting stroke, receives the cut blanks and carries them to the bumping and crimping station where they are acted upon by the pressing die 44, the bumper or bumping die 41 and the punching or drawing 80 die 43.

In the form of the invention shown the pockets 75 are merely holes in the rotating dial 3, the blanks being supported on and slid over the face of a stationary table or 85 plate 150. With the pockets arranged at 90° as shown and the bumping and cutting stations 180° apart there are necessarily two stations, one at the front and one at the rear 90 where no operation takes place. The relative location of the pockets, the number of pockets in the dial and the relative location of the cutting and pressing members, also the timing of the parts are widely variable 95 and may be regarded as matters of selection or design.

As aforesaid the bumper precedes the punch, being set some 30 to 60° ahead of it and also the bumper actuating mechanism is 100 constructed with a considerable amount of play or back lash which is taken up by springs 38 so that after the stroke of the bumper when the positive thrust of the mechanism is released, the bumping die is 105 held against the paper pressing it against the stationary die by the action of the springs giving a resilient or yielding rather than a positive grip so that the punch which follows the bumper serves to draw the paper through and between the cooperating serrated surfaces 45 creasing or crimping the paper much more effectively than it can be done by direct pressure. The adjustments described in this connection compensate for any desired thickness of web or variation in 110 thickness.

The cut waste is removed by any suitable take-off mechanism as aforesaid, indicated and described in connection with reference characters 140 to 145.

It is also noted that the feeding mechanism provides for the adjustment of the rolls as to spacing and pressure so that web of any desired thickness can be used, meaning 125 that any number of sheets which can be properly cut and crimped may be fed through the machine. Paper cups or wrappers which constitute the product of the machine indicated by reference character 160 are shown in the form of a single cup in 130

Fig. 10 and a plurality of cups in Fig. 11, the latter in the arrangement which they come from the machine.

Important advantages of the machine are 5 convenience for arrangement, the perfection of the product, particularly as to efficiency of the crimping operation, universal adjustability and extra length of life and possibility of cheap construction due to simplicity of design.

I claim:

1. In a machine for crimping paper and the like in the manufacture of paper wrappers, means for feeding a web, a reciprocating cutter and a cooperating die, reciprocating crimping mechanism, means for carrying the cut blanks from the cutting mechanism to the crimping mechanism, the same having an intermittent motion and means for 15 timing the parts so that the cutter and the crimping mechanism operate during the dwell of the carrier.

2. In a machine for crimping papers and the like in the manufacture of paper wrappers, means for feeding a web, a reciprocating cutter and a cooperating die, reciprocating crimping mechanism, means for carrying the cut blanks from the cutting mechanism to the crimping mechanism, the same 20 having an intermittent motion, means for timing the cutter to operate during the dwell of the carrier and means for arresting the motion of the carrier at each dwell in operative relation to the crimping mechanism.

3. In a machine for crimping paper and the like in the manufacture of paper wrappers, a reciprocating cutter, reciprocating crimping mechanism, means for feeding paper to the cutter, a dial having a step by step rotation with the pockets to receive the blanks from the cutter and carry them to the crimping mechanism, means for timing the cutter to operate during the dwell of the die when an aperture of the dial is in alignment with the cutter and means for arresting the motion of the dial with a pocket in alignment with the crimping mechanism.

4. In a machine for crimping papers and the like in the manufacture of paper receptacles, a reciprocating cutting means and reciprocating crimping means and separate driving means for each said cutting and crimping means, a carrier having a step by 50 step motion and having means for receiving the cut blanks and carrying them to the crimping mechanism and means for timing the parts in cooperative relation.

5. In a machine for crimping paper and the like in the manufacture of paper receptacles, a reciprocating cutting means and reciprocating crimping means and separate driving means for each said cutting and crimping means, a carrier having a step by 60 step motion having means for receiving the

cut blanks and carrying them to the crimping mechanism and means for timing the cutter and actuating it to operate during the dwell of the carrier and means for positioning the carrier in operative relation to and with the crimping mechanism from time to time as it comes to rest.

6. In a machine for forming paper receptacles, a carrier for blanks having a step by step motion, a reciprocating cutter and means for driving the reciprocating cutter including a continuously rotating member, a rotatable member connected to the cutter to drive the same and means for connecting the continuously rotating member to the rotatable member at intervals corresponding to the dwell of the carrier.

7. In a machine for forming paper receptacles, a carrier for blanks having a step by step motion, a reciprocating cutter and means for driving the reciprocating cutter including a continuously rotating member, a rotatable member connected to the cutter to drive the same and means for connecting the continuously rotating member to the rotatable member at intervals corresponding to the dwell of the carrier, the same consisting of a sliding bolt, a cam member on the bolt, means actuated by the carrier at intervals corresponding to the dwell of the carrier to move said latter cam member into and out of the path of the cam member on the bolt.

8. In a machine for cutting paper blanks, a carrier having a step by step motion, a reciprocating cutter, a die, a carrier having a receptacle which stops during the dwell of the carrier in registration with the die to receive the blanks, means for timing the cutter relatively to the carrier and driving the cutter, consisting of a continuously rotating member, a rotatable member connected to the cutter to drive the same and means for connecting the continuously rotating member to the rotatable member at intervals, consisting of a reciprocating bolt, a bolt actuating member adapted to be moved into and out of the path of the bolt and means on the carrier and tripping mechanism cooperating therewith to move said bolt actuating member out of the path of the bolt just prior to the dwell of the carrier.

9. In a machine for cutting paper blanks, a carrier having a step by step motion, a reciprocating cutter, a die, a carrier having a receptacle which stops during the dwell of the carrier in registration with the die to receive the blanks, means for timing the cutter relatively to the carrier and driving the cutter, consisting of a continuously rotating member, a rotatable member connected to the cutter to drive the same and means for connecting the continuously rotating member to the rotatable member at intervals, consisting of a reciprocating bolt, a bolt actuating member adapted to be

- 5 moved into and out of the path of the bolt and means on the carrier and tripping mechanism cooperating therewith to move said bolt actuating member out of the path of the bolt just prior to the dwell of the carrier, means tending to move the bolt into engagement with said continuously rotating member.
10. In a machine for cutting paper blanks and forming paper receptacles therefrom, a carrier having a step by step motion, a reciprocating cutter, a die, the carrier having a receptacle which stops during the dwell of the carrier in registration with the die to receive the blanks, means for timing the cutter relatively to the carrier and driving the cutter, consisting of a continuously rotating member, a rotatable member connected to the cutter to drive the same and means for connecting the continuously rotating member to the rotatable member at intervals, consisting of reciprocating bolt, a bolt actuating member adapted to be moved into and out of the path of the bolt and means on the carrier and tripping mechanism cooperating therewith to move said bolt actuating member out of the path of the bolt at intervals corresponding to the dwell of the carrier, crimping mechanism including a reciprocating die also in cooperative relation with the carrier and means carried by the reciprocating portion of the crimping mechanism for positioning the carrier during its dwell in cooperative relation with the crimping mechanism.
